United States Patent Office

Des. 214,740

Patented July 22, 1969

214,740

BENCH

James B. Douglas, 5840 McLynn Ave.,
Montreal 29, Quebec, Canada

Filed July 17, 1967, Ser. No. 7,834

Claims priority, application Canada Jan. 17, 1967

Term of patent 14 years

Int. Cl. D6—01

U.S. Cl. D33—11

The figure is a perspective view of a bench showing my design.

The bench is substantially the same in appearance when viewed from a diagonally opposite position.

The dominant feature of my design resides in the features shown in full line on the drawing.

I claim:

The ornamental design for a bench, as shown and described.
